UNITED STATES PATENT OFFICE.

JOHN CHRISTIE ADAM, OF NORTH KENSINGTON, LONDON, ENGLAND.

CARBURETER.

1,241,461.

Specification of Letters Patent. Patented Sept. 25, 1917.

Application filed March 27, 1917. Serial No. 157,677.

To all whom it may concern:

Be it known that I, JOHN CHRISTIE ADAM, a subject of the King of Great Britain, residing at 75 Highlever road, North Kensington, in the county of London, England, have invented certain new and useful Improvements in Carbureters, of which the following is a specification.

This invention relates to carbureters.

10 The object of the invention is to provide an improved form of carbureter which is simple to manufacture and generally efficient in operation.

According to this invention a carbureter 15 comprises a movable choke device having a central space of cross sectional area varying along its axis within which a fuel jet is arranged and having passages through it which are adapted to be uncovered or covered progressively as the choke device is moved relatively to the fuel jet and means for maintaining the number of said passages which are uncovered constant though the choke device is moved relatively to the jet.

25 The movement of the choke device may also vary the amount of the mixture or air passing to the engine. The choke tube or member preferably comprises a number of annular plates arranged one above another,

30 spaced apart and of different internal diameters, the fuel jet being arranged on the axis of the plates and the choke device thus formed being movable within a cylinder so that the passage through the plates can be 35 varied by withdrawing the choke device more or less from the cylinder.

The choke device may be arranged to be moved automatically by the suction of the engine.

40 The invention will be fully understood from the following description taken in connection with the accompanying drawings which illustrate by way of example, methods of carrying the invention into effect and in 45 which:—

Figure 1 is a sectional elevation of one form of carbureter constructed according to this invention.

Fig. 2 is an elevation partly in section of 50 the same, looking in the direction of the arrow X in Fig. 1.

Fig. 3 is an under plan view of the movable choke device of the same, and

55 Figs. 4, 5 and 6 are part sectional elevations of three other forms respectively of

carbureter constructed according to this invention.

Referring to Figs. 1, 2 and 3 the carbureter comprises a body 1 having two cylindrical parts 2 and 3. Centrally arranged 60 within the cylindrical part 2 is a fuel jet 4 which is fed with fuel through a pipe 5 leading from a float chamber 6. The float chamber 6 is only indicated diagrammatically as it may be of any suitable construction. The body of the float chamber may be formed or cast in one piece with the body 1 of the carbureter or it may be separate therefrom. An inlet for air is provided 65 at 7 and an opening at 8 leads to the induction pipe. Slidable within the cylindrical part 3 is a cylindrical cup-shaped part or piston 9 and slidable within the cylindrical part 2 is a sleeve 10. A number of annular plates 11 are fixed to the base of the part 9 70 by bolts 12, these plates being spaced apart by washers 13 surrounding the bolts 12 and placed between the plates 11. The heads of the bolts 12 abut against a ring 14 supporting the lowermost annular plate 11. The 75 three or four uppermost plates 11 are preferably closer together than the lower ones. The external diameters of the plates 11 are all the same and the plates fit the sleeve 10 but can slide therein. The internal diam- 80 eters of the plates 11 increase downward so as to leave a conical space surrounding the fuel jet 4. The plates 11 therefore form a movable conical choke device surrounding the fuel jet. The piston 9 and with it the 85 choke device are moved by a crank or arm 15 pivoted at 16 and connected by a link 17 with the base of the part 9. The lower end of the link 17 is provided with a cross-piece or head 18 which is received by a cap 19 90 made in two parts and fixed by screws to the part 9. The top of the part 3 is provided with a screwed cap 20 which is slotted to allow the crank 15 to pass through it. The crank 15 is connected in any suitable manner to a hand-operated lever or other suitable operating device. The sleeve 10 is provided with pins 20' which project through slots 21 in the cylindrical part 2 and these pins are connected in any suitable manner 100 with a hand or other operating device. The part 9 and the sleeve 10 may be moved or operated by Bowden wires connected to a lever giving dual control by having movement in two planes, movement of the lever 110

in one plane serving to move the part 9 and movement in the other plane serving to move the sleeve 10. Such an arrangement is diagrammatically illustrated in dotted lines in Fig. 2. The crank 15 has an arm 15¹ attached to it, which arm is connected by a Bowden wire 15² to the operating lever 15³. The pins 20' on the part 10 are also connected by the horseshoe frame 20² and Bowden wire 20³ to the lever 15³. The lever 15³ has a part 15⁴ attached to it, which part has two grooves 15⁵ and 15⁶ at right angles in which slide blocks 15⁷ and 15⁸, to which blocks the ends of the Bowden wires 15² and 20³ are attached respectively. The part 15⁴ can be moved by the lever 15³ in the direction of either of the grooves 15⁵ and 15⁶ and accordingly either of the Bowden wires can be operated as described. The connection of the Bowden wires to the operating lever 15³ is only diagrammatically indicated as suitable arrangements are well known in connection with control of aeroplanes. The arrangement just referred to is suitable for use on aeroplanes. Apart from the mechanism described no throttle valve need be provided.

The carbureter operates as follows:—

With the parts in the position shown in Fig. 1 the supply of mixture to the engine is entirely cut off. If the part 9 and with it the choke device are slightly raised air entering by the inlet 7 together with fuel from the fuel jet passes between the plates 11 into the space 22 and thence to the induction pipe through the outlet 8. As the part 9 is raised an increasing number of the outer edges of the plates 11 are uncovered thereby providing a passage for the mixture in area of cross-section. At the same time the choking effect of the choke device is varied owing to the conical shape of the central space within the choke device. By moving the sleeve 10 with the choke device after the latter has been raised the throttling effect can be maintained constant though the choke device is moved relatively to the jet.

The carbureter may be arranged to operate automatically, as illustrated for example in Fig. 4. The cylindrical part 3' is closed by a screw cap 20⁴ and holes 23 are provided in the part 9'. With this arrangement the suction of the engine withdraws air from above the part or piston 9' through the holes 23 thereby causing the part 9' and with it the choke device to rise. A spring 9² may be provided for controlling the movement of the choke device. With the carbureter arranged to act automatically an independent throttle valve is provided.

Referring to Fig. 5, the carbureter therein shown comprises a body 24 having two cylindrical parts 25 and 26 within which slides a cylinder or sleeve 27. A choke device comprising annular plates 11 and a cup-

shaped part 9, similar to the similarly marked parts of the carbureter shown in Figs. 1 to 3, can slide within the sleeve 27. The crank 15 instead of being pivoted on the body of the carbureter, as in Figs. 1 to 3, is pivoted at 28 on a cap 29 which screws on to the top of the sleeve 27. Three slots or openings 30 are provided in the sleeve 27. By rotating the crank 15 the choke device can be raised relatively to the sleeve 27 and thereby permit the passage of the mixture between the plates 11 and through the openings 30 to the space 31 and thence through the outlet 8 to the induction pipe, while at the same time the choking effect of the choke device on the fuel jet is varied. If the sleeve 27 is raised by raising the part 28 without permitting rotation of the crank 15 relatively thereto the amount of overlap of the openings 30 with respect to the choke device remains constant because the choke device in this case moves with the sleeve, while the choking effect on the fuel jet is varied. The rotation of the crank 15 may be effected by means of the arm 15⁹. The raising of the part 28 may be effected by the link 28' connected to the bell-crank lever 28², pivoted on the bracket 28³.

In the carbureter shown in Fig. 6 the general arrangement is similar to that shown in Figs. 1 to 3 but the plates 11 of the choke device are arranged so that their internal diameters decrease downward. The orifice of the fuel jet when the air supply is cut off stands near the center of the ring 32. In order that the fuel may be cut off a plate 33 is arranged above the fuel jet being attached thereto by arms 34, this plate fitting the orifice 35 in the ring 32. The choke device is moved downward to allow the passage of air, the air passing between the plates 11 before being mixed with the fuel. The sleeve 36 corresponds to the sleeve 10 shown in Figs. 1 to 3. The choke member is connected to the part 9 by long bolts so as to allow a free passage for the mixture to the induction pipe.

Instead of constructing this form of carbureter with a sleeve corresponding to the sleeve 10 in Figs. 1 and 2, it may be constructed with the choke-device and part 9 movable within a sleeve such as the sleeve 27 shown in Fig. 5.

The form of carbureter shown in Fig. 6 is particularly adapted for use on aeroplanes.

What I claim and desire to secure by Letters Patent of the United States is:—

1. A carbureter comprising a movable choke device having a central space of cross-sectional area varying along its axis within which a fuel jet is arranged and having passages through it which are adapted to be uncovered or covered progressively as the choke device is moved relatively to the fuel

- jet and means for maintaining the number of said passages which are uncovered constant though the choke tube is moved relatively to the jet.
5. A carbureter having a choke device comprising a number of annular plates arranged one above another, spaced apart and of different internal diameters within which a fuel is arranged, the device being movable within a cylinder so that by withdrawing it from the cylinder a passage of variable area of cross-section through the device is provided, and a sleeve interposed between the choke device and the said cylinder the movement of said sleeve serving to permit of the area of cross-section of the said passage being maintained constant though the choke device is moved relatively to the jet.
10. 3. A carbureter comprising a fitting consisting of two coaxial cylinders with an intermediate connecting portion adapted to be joined to an induction pipe, a fuel jet arranged within one cylinder and surrounded by a choke device movable in this cylinder and connected to a piston movable in the second cylinder, the choke device comprising a number of annular plates arranged one above another, spaced apart and of different internal diameters, the arrangement being
15. such that as the choke device is withdrawn from the cylinder within which it moves a passage of varying area of cross-section to the induction pipe is provided and the choking effect on the fuel jet is varied and a sleeve interposed between the choke device and the second cylinder, the movement of said sleeve serving to permit of the area of cross-section of the said passage being maintained constant though the choke device is moved relatively to the jet.
20. 4. A carbureter having a choke device comprising a number of annular plates arranged one above another, spaced apart and of different internal diameters within which a fuel jet is arranged, a cylinder within which the choke device can move and a sleeve having openings through it interposed between the choke device and the cylinder, the arrangement being such that as the choke tube is withdrawn from the cylinder a passage of varying area of cross-section to the induction pipe is provided and the choking effect on the fuel jet is varied while by moving the said sleeve the area of cross-section of the said passage may be maintained constant though the choke device is moved relatively to the jet.
25. 40. 45. 50. 55.

JOHN CHRISTIE ADAM.
